FOLDING NEST

Thomas E. Garrety, Springfield, Ohio, assignor to Buck-eye Manufacturing Company, Kansas City, Mo., a corporation of Delaware

Filed Jan. 31, 1962, Ser. No. 170,136
7 Claims. (Cl. 119—45)

This invention pertains to nests and more particularly to a partially foldable poultry egg laying nest.

The common poultry nest is shipped from the factory in the knocked-down or unassembled condition. Due to the number of parts, such nests have always been difficult and time consuming to assemble in the poultry house. For example, it is not uncommon for a ten hole hen nest to be supplied with 112 nuts and bolts, and require anywhere from 45 minutes to 1½ hours to assemble, depending upon the skill and experience of the person or persons making the assembly. A large poultry house may assemble 500 to 600 such nests at a time, and with one man being able to assemble between 5 and 8 such nests a day, it is seen that this results in a considerable investment in labor and time in addition to the purchase price of the nest.

It is therefore a principal object of this invention to provide a poultry nest of simplified construction which eliminates most of the connections common to the assembly of ordinary nests and which may be shipped in a partially folded condition resulting in a considerable savings in labor and time in assembling and erecting. This is accomplished, in part, by the provision of a folded partition and end wall assembly which may be set up in an operative condition in a single movement to provide the basic framework to which the remaining elements of the nest may be readily and easily assembled.

A further object of this invention is the provision of a nest having parts thereof which become a permanent attachment to the partition assembly by the bending of tabs, with the elimination of nut and bolt connections. An advantage of this construction resides in its increased rigidity over the comparable bolt and nut construction, and increased cleanliness and safety, characterized by the freedom from objectionable projecting parts.

A further object of this invention is the provision of a nest having a minimum of differing parts, utilizing parts formed from substantially identical stampings in a plurality of locations, and which is adapted to be assembled without bolts using a minimum of common hand tools.

A still further object of this invention is the provision of a nest, as outlined above, which is rigidly self-supporting in the erected position wherein the components thereof are readily assembled and locked into engagement forming a rigid self-supporting structure free of removable fastener devices.

Other objects and advantages of the invention will be apparent from the following description, the accompanying drawings, and the appended claims.

In the drawings—

FIG. 1 is a perspective view, partially broken away to expose details of construction, of an assembled nest constructed according to this invention;

FIG. 2 is an elevational view of the folded divider and end wall assembly of this invention, prior to erection, with the right end wall being shown in the extended position in broken lines;

FIG. 3 is a fragmentary view of the left end wall and next adjacent divider of FIG. 2 in the expanded position showing the arrangement of one of the articulated straps therebetween, with a portion of the strap being broken away;

FIG. 4 is a section taken generally along the line 4—4 of FIG. 3;

2

FIG. 5 is an elevational end view looking at the left-hand end of the assembled unit of FIG. 1;

FIG. 6 is a fragmentary perspective view looking at the inside surface of one of the front and back members;

FIG. 7 is a fragmentary elevational view looking from the inside of the nest showing the manner in which the member of FIG. 6 is supported on one of the connecting straps of the divider assembly, taken generally along the line 7—7 of FIG. 5;

FIG. 8 is a section taken generally along the line 8—8 of FIG. 7;

FIG. 9 is a fragmentary view looking into one of the corners made by one of the ends and one of the front or back members of FIG. 6;

FIG. 10 is a section through the upper perch taken generally along the line 10—10 of FIG. 5;

FIG. 11 is a perspective fragmentary view looking at the inside of the nest top;

FIG. 12 is a fragmentary vertical section through the top subsequent to installation;

FIG. 13 is a fragmentary perspective showing the connection of the top at one of the dividers;

FIG. 14 is a fragmentary transverse section through the nest looking generally in the same direction as in FIG. 5 and showing the position of one of the removable nest bottoms, taken generally along the line 14—14 of FIG. 15;

FIG. 15 is a further section generally along the line 15—15, of FIG. 14, with the removable bottom being shown in broken lines prior to insertion;

FIGS. 16 and 17 are similar respectively to FIGS. 11 and 12 showing a modification of the top portion of the invention;

FIG. 18 is a perspective inside view of one of the modified partitions; and

FIG. 19 is an elevational view of the modified hanger strap used with the top of FIGS. 16—18.

The views of FIGS. 2—19 are drawn to enlarged scales as compared to FIG. 1 for the purpose of clear illustration.

Referring to the drawings, which illustrate preferred embodiments of this invention, an assembled nest constructed according to this invention is shown in FIG. 1 as being mounted on a wall 20. A plurality of such nests may be mounted on a wall or supported on a floor or on each other, as desired. The nest of FIG. 1 includes ten individual nesting compartments 22 arranged in two horizontal superimposed rows of five each, although this number and arrangement may vary within the scope and teachings of this invention.

Referring to FIG. 2, the principal structural component of the nest of this invention consists of a foldable divider and end wall assembly 25. The assembly 25 consists of a plurality of similarly formed vertically extending partitions 26 which make up the partitions separating the adjacent compartments 22. Two of the partitions 26 form the left and right ends 28 and 29 respectively of the nest.

The partitions 26, including the ends 28 and 29, are each formed with transversely turned peripheral edges forming flanges along the four sides thereof, with straight sides and a forwardly sloping top. They are connected to each other by pairs of separate top and bottom straps 30 and 31, there being two top straps 30 and two bottom straps 31 extending between each adjacent pairs of the partitions 26.

Referring to FIGS. 3 and 4, it can be seen that the partitions 26 are formed with inwardly turned or flanged edges 34 including hems 35 so that the edge thereof provides a smooth surface for the entrance to the compartments 22. The straps 30 and 31 are pivotally mounted on the edges 34 of the partitions and end walls by rivets 36, and the straps may extend from the outer surface of

one of the front edges 34 of the partitions to the inside surface of the next adjacent partition, as shown in FIGS. 2 and 4. Thus, the assembly 25 is movable between a compact folded position with the partitions in contiguous relation, as shown in full lines in FIG. 2, to a spaced-apart or open position as shown in FIG. 1, with the spacing being defined by the straps 30 and 31. In the latter condition of assembly, the straps 30 and 31 form top and bottom horizontal extending parallel rows of straps.

The assembly 25 is held and supported in the expanded position by pairs of front and back members, all of substantially identical construction. Two front members are employed in this embodiment, including an upper front member 40 and a lower front member 41. Identical back members, corresponding to the front members, may be employed as shown in FIG. 5 including an upper back member 44 and a lower back member 45. The front and back members are supported on, and conceal the respective straps 30 and 31 and provide the closures for the nest compartments 22.

An end portion of one of the members is shown in FIG. 6 as having a downwardly turned upper rim 48 which is cut out or notched at 49 to receive the flanged edges 34 of the partitions 26. The downwardly turned rim 48 is thus separated into segments, and provides means which are proportioned to be engaged over one of the straps 30 or 31 between the partitions, as shown in FIG. 7.

The bottom edge of each of the members forms an inwardly turned ledge portion 50 which has tabs 51 cut therein and bent upwardly, as shown in FIG. 6, thereby defining open spaces 52 within the ledge portion 50 for receiving the flanged front and back edges 34 of the partitions, in the manner of the spaces 49. The tabs 51 are bendable transversely by hand into interfering engagement with the partitions inwardly of the edges 34, as shown in FIG. 7, to hold the assembly 25 rigid in its expanded position. A corner detail is shown in FIG. 9, which may be any one of the four lower corners of the nest, showing the manner in which the adjacent tab 51 is received into the corner of the end panels 28 or 29.

The sloping top 60 is secured to the assembly 25 in a manner similar to that described in connection with the front and back members. The top 60 is formed with downwardly turned end flanges 61 at the opposite ends thereof, as shown in FIGS. 1, 5 and 11. In addition, the top 60 is formed with front and back downwardly and inwardly turned rims 64 and 65, as clearly shown in FIG. 11. The front and rear rims have tabs 70 cut therein defining cut-out openings 71 having a spaced apart distance equal to that of the partitions for receiving the turned upper ends of the partitions, as shown in FIGS. 12 and 13. The tabs 70 are bendable transversely to the partitions into contact therewith for holding the assembly 25 rigid at the top, as shown in FIG. 13.

The removable nest pans or bottoms 75 are best shown in FIGS. 14 and 15 as having upwardly turned left and right ends 76. The bottoms have a depth corresponding to the depth of the partitions, and are received and supported along their front and rear edges, as shown in FIG. 14, on the inwardly turned ledge portions 50 of the front and rear members.

A double tiered nest, as described herein, is usually provided with a perch for each row of compartments 22. The lower perch 80 is preferably a double perch making it possible for the hens to jump from the lower perch to the single upper perch 82.

The perches include a pair of vertical angle-section supports 85 each of which includes an upper single perch supporting arm 86 and a lower double perch supporting arm 87 pivotally mounted thereon, as indicated in FIG. 5. The upper arm 86 includes a flared opening within which is received the customary wooden perch slat 90 therethrough extending between the opposite arms of the perch supports. This slat may be fixed thereto by a con-

ventional bolt 91 and nut 92 as indicated in FIG. 10. The lower perch arms similarly include and support a pair of such perch slats.

The angle sections supports 85 of the perches may be suitably secured to the nest along the front edge 34 of one of the partitions by suitable fastening means. Each of the perch arms 86 and 87 includes a pressed detent 95 which cooperates with a recess 96 formed in the supports 85 to hold the perches in the raised position, as shown in broken outline form in FIG. 5, when it is desired to close the nest.

In the practice of this invention, a majority of the partitions 26 may be formed in identical manner to each other. Thus, in the embodiment illustrated, all of the partitions 26 and the right end 29 may have all of the flanged edges thereof turned in one direction, and the left end 28 may be formed with the flanges turned inwardly in the other direction.

The assembly 25 is preferably shipped in the collapsed condition and is readily expanded to its full length by withdrawing the left and right ends. The front and back members may then be inserted by looping the rims 48 over the connecting links 30 and 31 and by bending the tabs 51 transversely into interfering engagement with the wall of the adjacent partition inwardly of the edges 34. No allowance at the tabs 51 is made for the thickness of the material of the partitions, thus providing an interference fit at the end of the tab 51, and providing a rigid and self-supporting nest structure. In this manner, each of the front members 40, 41 and back members 44, 45 may be quickly and permanently installed.

The top 60 may then be put in position, or if desired, it may be put in position prior to the installation of the front and back members. The tabs 70 of the top 60 are similarly bent outwardly into interfering engagement with the adjacent partitions or ends, thus locking the top in assembled position. Thus nest pans or bottoms 75 are inserted by lowering through the front openings of the nests. The perch supports 85 may then be readily attached to the assembled and erected nest by suitable attaching bolts and the wood perch slats may be installed. The perch is then ready to hang on a wall for use.

The modification of the top construction shown in FIGS. 16-19 has certain advantages in that the top 60' is more readily and quickly assembled to the sloping top of the partitions and locked into position without the necessity of manipulating or bending tabs. The top 60' in FIG. 16 is formed with a downwardly and inwardly turned front edge or rim 100, which may be formed similarly to the edge 65 of the top 60, except that no tabs are formed therein. The rearward edge of the top 60', as well as the sides, terminate in a downwardly turned rim 102.

The modified partitions 26' are each formed with a notch or recess 103 in the front edge thereof adjacent their top edge to receive the inwardly turned rims 100. The assembled position of the top 60' on one of the partitions 26' is shown in FIG. 17 with the rim 100 hooked in the notches 103 and with the back rim 102 received over the outer back edge of the partitions 26'. Thus, the rim 100 comprises means on the top engageable with the partitions adjacent the upper edge thereof for holding the top and partitions in assembled relation.

The partitions are preferably provided with further top retainer means engageable with the top 60' along the back edge thereof for securing the top in the assembled position, as shown in FIG. 17. This consists of the hanger straps 105, FIG. 19, which are pivotally mounted to each of the partitions 26' by a rivet 106. The hanger straps 105 are normally folded downwardly but may be raised to an erected position for hanging, as shown in FIG. 17, and are provided with a lanced metal tongue 110 which snaps out over the top 60' when erected to secure the top in place.

The nest of this invention is superior to those which are bolted together because of its greater rigidity by reason of increased metal-to-metal contact. It can be shipped in the same type of containers as were used with the previous nests and requires only five minutes time for complete assembly and erection, as compared to approximately 45 minutes to 1½ hours for the nut and bolt type of construction. The elimination of most of the removable fastening elements results in a nest unit which is safer for the poultry, and is easier to keep clean.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A laying nest adapted for rapid erection free of removable fastening devices, comprising a divider assembly consisting of a plurality of vertically extending partitions, a plurality of straps extending in pairs between and pivoted at adjacent said partitions providing for opening movement of said assembly from a folded compact position into an operative position with said separators in spaced apart relation as defined by said straps, nest front and back members extending the length of said opened assembly and each having means engageable with said assembly at said straps and each having bendable portions engageable with said partitions to hold said assembly rigid in said extended position, and a top extending the length of said opened assembly and having means engageable with said partitions adjacent the upper edge thereof for holding said partitions and said top in assembled relation.

2. A laying nest adapted for rapid erection free of removable fastening devices, comprising a divider assembly consisting of a plurality of vertically extending partitions, a plurality of straps extending between said partitions and pivoted at adjacent said partitions providing for opening movement of said assembly from a folded compact position into an operative position with said separators in spaced apart relation as defined by said straps, nest front and back members extending the length of said opened assembly and each having downwardly turned rim means engageable with said assembly at said straps for support thereon and further having an inwardly turned ledge having tabs thereon movable into interfering engagement with said partitions to hold said assembly rigid in said extended position, and top means extending the length of said opened assembly and engageable with said partitions.

3. A laying nest adapted for rapid erection free of removable fastening devices, comprising a divider assembly consisting of a plurality of vertically extending partitions connected to each other by separate top and bottom straps extending therebetween and pivoted at adjacent said partitions providing for opening movement of said assembly from a folded compact position into an operative position with said separators in spaced apart relation, nest front and back members extending the length of said opened assembly and each having means engageable with said assembly at said straps and each having a bottom inwardly turned ledge defining tabs bendable transversely into interfering engagement with said partitions to hold said assembly rigid in said extended position, a top extending the length of said opened assembly having front and back downwardly and inwardly turned rim portions defining tabs bendable transversely into contact with said partitions adjacent the upper edges thereof, and separate nest bottoms removably received between each of said partitions and proportioned for support on said ledges of said front and back members.

4. A laying nest adapted for rapid erection free of removable fastening devices, comprising a divider assembly

consisting of a plurality of vertically extending partitions connected to each other along the front and back edges thereof by opposite pairs of top and bottom straps extending therebetween and pivoted at adjacent said partitions providing for opening movement of said assembly from a folded compact position into an operative position with said separators in equally spaced apart relation defined by the length of said straps forming longitudinally extending rows of straps, nest front and back members extending the length of said opened assembly and each having a downwardly turned rim engageable with said extended assembly along said rows of straps and each having a bottom inwardly turned ledge defining tabs bendable transversely into interfering engagement with the adjacent said partitions to hold said assembly rigid in said extended position, a top extending the length of said opened assembly and formed with front and back downwardly turned rim portions engageable with said partitions, and separate nest bottoms removably received between each of said partitions and proportioned for supporting engagement with said ledges of said front and back members.

5. A sheet metal laying nest adapted for rapid erection free of removable connectors, comprising a divider assembly having a plurality of vertically extending partitions each having transversely turned front and back flanges, said partitions connected to each other by pairs of separate top and bottom straps pivoted at said flanges providing for movement of said assembly from a folded compact position with said partitions in contiguous relation into an operative position with said partitions being spaced apart a distance defined by the length of said straps, upper and lower nest front and back members substantially identical in construction to each other and extending the length of said opened assembly, each of said members having a downwardly turned upper rim engageable with said assembly along one of said top and bottom straps and each having a bottom inwardly turned ledge defining tabs bendable transversely into interfering engagement with said partitions inwardly of said flanges to hold said assembly rigid in said opened position, a top extending the length of said opened assembly and formed with front and back rim portions engageable with said partitions, and nest bottoms received between each of said partitions and proportioned to engage said inwardly turned flanges of said front and back members.

6. A sheet metal laying nest adapted for rapid erection free of removable connection, comprising a divider assembly having a plurality of vertically extending partitions each having transversely turned peripheral flanges, said partitions connected to each other by pairs of separate top and bottom straps extending from the fronts and backs of said partitions and pivoted at said flanges providing for movement of said assembly from a folded compact position with said partitions in contiguous relation into an operative position with said separators being spaced apart a distance defined by the length of said straps, upper and lower nest front and back members substantially identical in construction and extending the length of said opened assembly, each of said members having a plurality of downwardly turned upper rims separated by notches engageable with said assembly along said straps with said partitions received in said notches, each of said members having a bottom inwardly turned ledge defining tabs bendable transversely into interfering engagement with said partitions inwardly of said flanges to hold said assembly rigid in said expanded position, means in the front edges of said partitions defining a notch adjacent the upper edge thereof, a top extending the length of said opened assembly and formed with a downwardly and inwardly turned rim along the front edge thereof received in said partition notches, and means on said partitions engageable with said top at positions along the back edge thereof securing said top in assembled position on said partitions.

7. A laying nest adapted for rapid erection free of

removable fastening devices, comprising a divider assembly including a plurality of vertically extending partitions connected to each other by articulated members extending therebetween and pivoted at adjacent said partitions providing for opening movement of said assembly from a folded compact position into an operative position with said separators in spaced apart relation, nest front and back members extending the length of said opened assembly and having means engageable therewith to hold said assembly rigid in said opened position, means in the front edges of said partitions defining notches adjacent the upper edge thereof, a top extending the length of said assembly and having a downwardly and inwardly turned front rim received within said notches and a downwardly

5 turned rear rim received over the back edge of said partitions and combined hanger and top retainer straps secured to the back of said partitions including downwardly extending tongues engageable with said top for securing said top in the assembled position on said partitions.
